UNITED STATES PATENT OFFICE.

JOHN M. MOORE, OF ATLANTA, GEORGIA.

COPYING-PRESS.

SPECIFICATION forming part of Letters Patent No. 602,414, dated April 12, 1898.

Application filed June 21, 1897. Serial No. 641,704. (No model.)

To all whom it may concern:

Be it known that I, JOHN M. MOORE, a citizen of the United States of America, and a resident of Atlanta, in the county of Fulton 5 and State of Georgia, have made a certain new and useful Improvement in Letter-Copying Machines; and I do hereby declare the following to be a full, clear, and exact description of the invention, such as will enable others skilled in the art to which it 10 pertains to make and use the same, reference being had to the accompanying drawings, and to letters of reference marked thereon, which form a part of this specification.

15 This invention relates to devices for copying letters on tissue-paper; and it consists of the device and, further, in its details of construction hereinafter specified.

In the accompanying drawings, Figure 1 is 20 an interior side elevation of the device, one side of the casing being removed. Fig. 2 is a plan thereof with a portion of the casing removed. Fig. 3 is a sectional detail of the means for pivoting the levers forming the 25 side of the table and the frame proper of the operative parts. Fig. 4 is a sectional detail on the line 4 4, Fig. 1. Fig. 5 is a section of the spring-barrel on the line 5 5, Fig. 4. Fig. 6 is a detail in side elevation of the frame, 30 showing the spring-pressed roller, a portion of the main roller, and of the blanket. Fig. 7 is a detail of the main roller, showing the attachment of the blanket to the said roller; and Fig. 8 is an end view of said roller, showing 35 the pin and eyelet forming the means of said attachment.

In the figures like reference characters are uniformly employed in the designation of corresponding elements of construction in all the 40 views.

A is the casing, which is composed of sides *a*, a bottom *a'*, and an end piece *a''*. The sides *a* are extended upwardly and are rounded at one end, forming a hood by means of the 45 cover *a³*, which may be made removable, if desired, and, as shown in the accompanying drawings, hinged to a short section *a⁴* at *a⁵*. The short section *a⁴* does not extend to the bottom *a'*, but there is below the lower edge 50 of same a rectangular opening into which passes, after the manner of a drawer, a wa-

ter-reservoir *a⁶*, said water-reservoir lying upon the bottom *a'* directly under the main roller B.

c are side pieces, of metal, formed substantially as shown in Fig. 1 and pivoted to the casing upon downwardly-projecting arms *c'*, as shown in Fig. 3. Between the inner ends of these arms is journaled the main roller B in a manner hereinafter specified, and superincumbent upon and secured to the other ends of these arms is a table *c²*, provided with hooks *c³* and *c⁴*, arranged in pairs upon its top, as best shown in Figs. 1 and 2. Pivoted in slotted holes *d* in these arms is a roller D, the 65 periphery of which has placed thereon a tube *d'*, of blotting-paper or other absorbent material, and bears against the periphery of the main roller B, a spring *d²* serving to hold the same in forcible contact. 70

If desired, a lip *a⁷* may project from the back edge of the reservoir *a⁶* at a point directly under said roller B, so as to catch any water which may drop therefrom and convey it back to the reservoir, the utility of which 75 may be seen after the description of the operation of the device. The upward projections *a⁸* of the side pieces *a* are slotted, as shown by broken lines in Fig. 1, and the arms *c* have lateral projections on their inner ends, 80 as shown in Figs. 2 and 4, which pass through these slots and, being provided with lips *c⁶*, form guides for the arms. These projections *c⁵* are axially perforated, and the journal-bearings *b* of the roller B are journaled therein, so that said roller will revolve freely 85 therein.

E is a casing or barrel which is secured, as shown in Fig. 4, to one end of one of the lateral projections *c⁵*. Into this barrel *e* projects 90 one end of the shaft *b*, and secured thereto is a coil-spring *e⁶*, its free end being secured to a pin *e⁷* in the side of the ratchet-wheel *e²*, which ratchet-wheel is mounted on a pivot *c³*, the other end of which pivot is provided with 95 a thumb-nut, by which said ratchet-wheel may be rotated in winding the spring, the pawl *e⁵* serving to prevent a backward rotation of said ratchet-wheel. Now it is obvious that this spring *e* will act to rotate the roller 100 B with its periphery in contact with the roller D.

F is a cloth blanket which is secured by one end to the peripheral surface of the roller B and is provided at its free end with a transversely-extending rod f. This blanket F is 5 preferably secured to the roller B by means of eyelets f² and pins f', which latter are set and inclined backwardly in the roller. This blanket passes from contact with the roller B over the roller D, which, as aforesaid, is 10 coated with an absorptive material, whereby an absorbent is interposed between the blanket and said roller, said blanket lying upon the upper side of the table c², the rod f being engaged, when desired, with either pair of 15 hooks c³ or c⁴.

The operation of this device is as follows: With the rod f engaged with the pair of hooks c³ the outer ends of the arms c are elevated, which depresses the roller B, so that its peripheral surface dips below the surface of the water in the reservoir a⁶. The rod is then pulled upon, so as to unroll the blanket F from the roller B, thus passing it through the water and passing it between the peripheral 20 surfaces of the rollers B and D, whereby it is wet and the excessive water squeezed therefrom, respectively. As soon as the said blanket is withdrawn a sufficient distance the rod f is engaged with the pair of hooks c⁴ and 25 that end of the arms depressed, raising the roller D out of the water in the reservoir a⁶ and stretching the said blanket along the upper side of the table c². The sheet of tissue-paper which is to receive the copy is then laid 30 flat upon the upper side of the blanket and the document to be copied laid face downwardly upon the said tissue-paper. The rod f is then disengaged from the hooks c⁴, and, the roller B being rotated by the action of the spring e⁶, 35 said blanket, with the superincumbent sheets of paper, (letter and tissue,) is passed between the rollers B and D and the impression of the letter taken upon the dampened sheet of tissue-paper, the whole being compressed by 40 being wound upon the roller B under a strong winding action, where it may be allowed to remain so long as experience shows it is necessary for the transfer to take place. The rod f is engaged with the hooks c³ and the tension of the spring e⁶ is sufficient to create the 45 desired amount of pressure due to winding. During this transfer the roller B is elevated out of the water. If necessary, by reason of the ink with which the document to be copied 50 is written being of the "oil-base" variety, the blanket may even be again moistened without disarranging the sheets of paper from their exactly proper relative position. As soon as 55 the transfer has taken place the blanket is withdrawn to the position shown in Fig. 1 and the document and copy removed from the device, when the machine is ready for another operation. The number of copies to be 60 taken is only limited by the number of the 65 blankets or the length thereof. Any water squeezed from the blanket between the rollers

B and D will run along the lip a⁷ to the reservoir a⁶.

When it is desired to gain access to the interior of the device, the hood a³ may be raised. 70

If desired, a roll-paper holder G may be secured to the casing, as shown by broken lines in rudimentary form in Fig. 1, and the cutter g may be employed, whereby the sheets of tissue-paper may be severed from the roll. 75

Many of the elements of this device may be varied without a departure from the spirit of the invention.

Having thus described my invention, what I claim as new, and desire to secure by Letters Patent of the United States, is—

1. In a letter-copying machine, a water-reservoir, a roller depressibly mounted thereover, a motor acting to rotate said roller, and a blanket secured to and adapted to be wound upon said roller and to be extended therefrom for copying purposes, for the purpose specified. 85

2. In a letter-copying machine, a water-reservoir, a roller depressibly mounted thereover, means for rotating said roller, a blanket secured to said roller and adapted to be wound thereon and to be extended for copying purposes and a roller mounted elastically and adapted to press said blanket against the periphery of said first-named roller, for the purpose specified. 95

3. In a letter-copying machine, a water-reservoir, a roller depressibly mounted thereover, means for rotating said roller, a blanket secured to said roller and adapted to be wound thereon and to be extended for copying purposes and a roller mounted elastically and adapted to press said blanket against the periphery of said first-named roller, and an absorptive covering for said pressure-roller, for the purpose specified. 100

4. In a letter-copying machine, a casing, a water-reservoir therein, a roller depressibly mounted therein over said water-reservoir, a motor adapted to rotate said roller, a blanket adapted to wind upon said roller, a rod in the free end of said blanket, and hooks secured to the frame at the limit of movement of the end thereof in winding upon and unwinding from the said roller, for the purpose specified. 110

5. In a letter-copying machine, a casing, a pair of levers mounted thereon, a table secured to and between same, a roller journaled on their opposite ends, a motor mounted on one of said levers and operatively connected to said roller, a blanket adapted to be wound upon said roller and drawn therefrom onto said table, and a water-reservoir below said roller, for the purpose specified. 120

In testimony whereof I hereunto affix my signature in presence of two witnesses.

JOHN M. MOORE.
